AUTOMATIC AWNING

Otto Vogel, Farmingdale, N. Y.

Application April 7, 1936, Serial No. 73,076

9 Claims. (Cl. 156—44)

My invention relates to automatic awnings and has for its primary object the protection of the interior of a room from the weather as, for example, in cases where a rain-storm occurs at a time when there is no one present to close the windows.

Another object of my invention is to provide means, operable by a very small amount of rain-water, to close an open window or other aperture with an awning guard and thus prevent damage to the interior by rain-water.

A still further object is to provide an automatic awning which, under ordinary conditions, will operate for long periods of time without any attention whatsoever.

A still further object is to provide an automatic awning the return of which to its normal non-protecting position occurs when rain ceases to fall.

Other objects and advantages of my invention will become apparent as the specification proceeds.

With the foregoing objects in view, my invention consists of the novel combination and arrangement of parts hereinafter described in their preferred embodiments, particularly pointed out in the appended claims, and illustrated in the accompanying drawings, wherein like parts are designated by the same reference characters throughout the several views.

In the said drawings:

Figure 1 is a front elevation, partly in section and partly broken away, showing the mechanism for operating my improved automatic awning;

Fig. 2 is a cross-sectional detail view of one of the side channel members showing the construction thereof;

Fig. 3 is a side elevation, partly in section and partly broken away, showing the awning rolled up;

Fig. 4 is a similar side elevation showing the awning lowered and disclosing certain parts obscured by those shown in Fig. 3; and,

Fig. 5 is a detail view of the means for arresting automatic operation of the awning.

Referring to these drawings, my invention comprises a horizontally disposed housing 11 the removable top of which constitutes a gutter 12, having in its bottom and near one end thereof an outlet 13, closed by a hinged stopper 14, on which latter is formed an integral lever arm 14', to which is attached a cord 15. Formed in the bottom of the gutter 12 are one or more outlets 16, spaced from the outlet 13 and from each other, which are normally closed by combination ball-

float stoppers 17 seating in said outlets 16 and adapted to float upward with a rise of level of rain-water in said gutter thus permitting such water to flow through said outlets 16. The stoppers 17 may be made of cork, balsa wood, or other naturally buoyant material, and are restricted in their upward movement by attached depending shanks 18 having split ends bent in opposite directions at right-angles to said shank which serve to retain said stoppers in their respective outlets.

Disposed under and spaced from the gutter 12 and constituting the bottom and part of the front wall of the housing 11, is a reservoir or tank 19 of rectangular shape having in its bottom an outlet 20, closed by a ball stopper 21, and an overflow pipe 22 adjacent the top of its rear wall. The ends of the tank 19 are also spaced from the opposite end walls and from the rear outer wall of said housing 11 (Figs. 3 and 4).

The upper ends of a pair of vertical channel members 23 (only one of which is shown) fit into the underside of the housing 11, one at each side and to the rear thereof, and are fastened as by screws, to the opposite sides of the window casing (see Fig. 2) or other aperture to which the device 25 may be affixed, while the housing is hung, as by hooks 24 fixed to its outside rear wall, on the upper and outer horizontal face of said casing.

Within the housing 11 and above the tank 19 to the rear thereof is mounted a roller 25 having 30 pulleys 26 keyed thereto at each end (only one of which is shown), said roller being pivoted in bearings fixed to the opposite side walls of the housing 11. Cords 27 fixed at one end to and wound on said pulleys 26 run over guide pulleys 35 26' and at their free ends are attached to weights 28 adapted to travel in shafts formed by said channel members 23.

An awning 29 made of any flexible material is fixed to and rolls on the roller 25, being adapted 40 to unroll from the rear of said roller, while the cords 27 are oppositely wound on said pulleys 26. Pulley 26, cord 27, and weight 28 on the right-hand end of roller 25—identical with those shown and therefore not duplicated in the drawings—45 serve merely as a counterweight to the awning 29. The left-hand cord and weight, however, in addition to their function as counterweight, also operate the control of my novel device, as will be hereinafter more fully explained.

Fixed on the lower part of said curtain or awning 29 adjacent its edge is a pocket or tank 30, of flat rectangular shape and having an open mouth 31 which tank 30 may be made of metal or any other suitable material impervious to 55

water, and has formed in its bottom one or more drip-outlets 32 controlled by weighted ball stoppers 33 having depending therefrom shanks 34 terminating in small ball weights 35. Upon the

5 rear surface of said pocket 30 at opposite sides are fixed hinged arms 36 which fold inwardly toward the center thereof and fasten one to the other when not in use.

The sides of the awning 29 run in grooves 31 formed by the channel members 23 and at the lower portion extending out from each side of the pocket 30 to the edges thereof said curtain is reinforced by a flange 30' of sheet metal or other stiff material. A roller 38 pivoted at its opposite 10 ends in bearings fixed on the inner side walls of the housing 11 serves to guide the awning 29 in the rear of the tank 19 and to align the side edges of the awning with the grooves 37.

A bracket 39 spans the tank 19 from front to rear at the top thereof. Centrally disposed on said bracket 39 is fixed an upright member 40 having upwardly and outwardly extending integral arms 41 in the crotch of which, by means of a horizontal pin 42, is mounted a hollow tube 43 having opposite sealed ends 44. Contained within said tube 43 is a ball weight 45, the travel of which is restricted between the sealed left-hand end of said tube and the central pin 42. The right-hand end 44 of the tube carries a bracket 30 46 in which rides the upper end of a link 47 which, guided by a guide-bracket 47' fixed to the inside front wall of the tank, is rigidly attached at its lower end to a ball stopper 21. In its normal position, when the ball stopper 21 is seated in the outlet 20 of the tank 19 closing the feed pipe 61, the tube is in horizontal balance, while the ball 45 rests against the pin 42. At the extreme left-hand end on the upper surface of the tube 43 is fixed a dish 48 which is also aligned directly 35 below the outlet 13 in the gutter 12, and which dish has formed therein one or more restricted drip-outlets 49. As will be clear from the foregoing description, the tube 43 is adapted to pivot on the pin 42 while the ball 45 rolls toward and 40 weighs down the left end thereof, as a consequence lifting the right-hand end which carries the link 47 and ball stopper 21 upward. To restore the tube to its original horizontal position, a vertical lever 50 slidable in guides 51 fixed on the outer end of the tank is provided, said lever 50 having an upper-forwardly-extending integral arm 52, the upper surface of which is disposed under the left end of the tube 43, and a lower, rearwardly-extending arm 53 having a downwardly turned foot projecting into the shaft 59 45 in the channel member 23 and into the path of the weight 28, which latter in travelling upward contacts with said foot and raises said lever 50 which in turn lifts the tube 43, as shown in dotted lines in Fig. 3, to its normal horizontal position, which also causes the ball 45 to roll to the right and settle against the pin 42.

Referring to Figs. 3 and 4, the cord 27 is fixed to pulley 26; at a prescribed distance from its said fixed end, as at 27', on said cord is fixed a bead or knot 54. The cord 15 is attached at one end to the lever arm 14'; its opposite end terminates in a loop 15' through which is threaded the cord 27; and thus, when with the unwinding of said cord 70 27, caused by dropping of the weight 28, the bead 54 contacts said loop and drags the same along, pulling cord 15, lifting the hinged stopper 14 and thus opening the outlet 13 in the gutter 12.

Referring to Figs. 2, 3 and 4, the particular construction of the upright channel members 23

is as follows: said members are first bent longitudinally to an L-shape to form an angle member 55 one side of which is bored to allow of fastening same as by screws to the window casing as above described; the member 23 is next bent from the 5 L-shape back upon itself to fit the corner and lie against the front face of the casement, forming a portion 56, which in turn is bent at right angles from the plane thereof and formed with spaced vertical knuckles 57. Knuckles 58 are formed 10 upon a separate channel member which is bent longitudinally to form the four sides of the shaft 59, said knuckles 57 and 58 when fitted together and secured by the usual hinge pin form a vertical piano hinge 60 which permits of the shafts 59 15 being swung outward so that the awning 29 may be pushed out of its groove and utilized as an awning when secured by the arms 36 to the usual fastenings (not shown) at the sides of the window casing. To permit of this outward movement of 20 the channel members forming the shafts 59 on the hinges the upper faces of said members are cut away as at 23', so that the cord 27 will not bind between the upper edges thereof and the bottom edge of housing 11.

To cause the device to remain inoperative, it is merely necessary to prevent the weight 28 from reaching the bottom of its shaft 59, so that the bead 54 may not pull cord 15 to open outlet 13; the left-hand channel 23 is cut away at its bottom 30 as at 23'' to permit of the rise of the end of a pivoted rocker-arm 65 which attends the closing of the window sash 66, or which may be manually controlled, and which arm 65 prevents the weight 28 from reaching the bottom of said shaft 35 59, as shown in Fig. 5.

Metal strips 62 formed with top and bottom flanges fastened as by screws to the casing may be used to clamp a window screen 63 against the portion 56 of the channel members 23. 40

A screen or sieve 64 extending from side to side may be fixed over the outlets in the gutter 12 (shown in Figs. 3 and 4) to protect same from stoppage by leaves, etc.

The operation of my invention is as follows: 45

The tank 19 must contain some water. The awning 29 is rolled up on the roller 25, the weights 28 are at the bottom of their respective shafts, the tube 43 is horizontal with the ball 45 resting against pin 42, while the bead 54 on cord 27 50 pulls down the cord 15, lever 14' and thus the outlet 13 in the gutter 12 is open. As it starts to rain, water falling into the gutter runs through the open outlet 13 and into dish 48 on the tube 43, whereupon said tube is thrown out of balance 55 and the ball 45 is started to roll toward the left-hand sealed end 44 of the tube, thus raising the opposite end thereof which in turn carries upward link 47 and ball-stopper 21 and opens outlet 20 of the tank 19, from which water rapidly 60 pours through pipe 61 the downwardly curved spout of which is disposed over the pocket 30 on the awning 29. Said pocket 30 quickly becomes sufficiently heavy with such water to outbalance the weights 28 and the awning descends 65 to protect the window. When the pocket 30 reaches and contacts with the window sill the stoppers 33, seated in outlets 32 in the bottom of said pocket, are forced upward opening said outlets and allowing water to drip slowly therefrom. As long as it rains, water running down the awning and from the overflow pipe 22 of the tank 19 replenishes the water in the pocket 30 and the awning will remain lowered. When the rain ceases, the rain water in the pocket 30 con- 70 75

tinuing to drip therefrom, said pocket again becomes lighter than the weights 28 which in turn descend under the influence of gravity, rolling up the awning, while the bead 54 again contacts loop 15' and opens the outlet 13.

When pocket 30 reaches the window sill the left-hand weight 28 in attaining its highest position pushes lever 50 upward, which in turn raises tube 43 and rolls ball 45 to their normal 10 positions, closing the outlet 20. Immediately the weight starts upward the bead 54 breaks its contact with loop 15' and under the influence of gravity the stopper 14 seats in the outlet 13 preventing actuation of the device. With outlet 13 closed, as rain continues to fall the rising level of water in gutter 12 raises ball-float stoppers 17 which are normally seated and the tank 19 is thereby replenished with water running through inlets 16. Because of the apertures in the dish member 48 the water caught therein drains out 20 after having served its purpose in initiating the downward movement of the tube.

The amount of water necessary to operate my novel awning is quickly replaced during a rain-storm; the capacity of the tank 19 as shown is calculated to provide for from 12 to 15 actuations of the awning without any replenishing by rain or otherwise. It is of course understood that the tank 19 may be replenished by a special pipe 30 connection with the main gutter from the roof of the house.

Although the drawings and the above specification disclose the best mode in which I have contemplated embodying my invention, I desire 35 to be in no way limited to the details of such disclosure for, in the further practical application of my invention, many changes in the constructional details of the device may be made as circumstances require or experience suggests, without departing from the spirit of the invention within the scope of the appended claims.

What I claim is:

1. A window guard in combination comprising a roller awning mounted in a housing, a receptacle attached to said awning having a plurality of drip outlets therein, counterweight means adapted to outbalance said awning and receptacle, a reservoir for water mounted in said housing, rain-actuated means for filling said receptacle 45 from said reservoir, means mounted in said housing and controlled by said counterweight means for rendering the rain-actuated means inoperative, means actuated by said counterweight means to reset said filling means and to shut off the 50 water supply from said reservoir.

2. A window guard comprising a roller awning of flexible material pivotally mounted in a housing, cord-attached counter-weights connected to the roller, an open-mouthed receptacle on the 55 lower edge of said awning having a plurality of controlled drip outlets therein, a reservoir for water, an outlet in said reservoir, rain-actuated means for filling said receptacle from said reservoir to a predetermined level to outbalance said counterweights and cause lowering of the awning, means actuated by one of said counterweights to reset said filling means in its normal position and to shut off the supply of water from said reservoir.

70 3. A window guard comprising a housing, channel members communicating therewith, a roller mounted in said housing, an awning on said roller, cord-attached counterweights connected to the roller, a flat receptacle on said awning having 75 controlled outlets therein, flanges integral with

the opposite ends of said receptacle and extending therefrom to the side edges of said awning to guide the latter in said channel members, a reservoir for water mounted in said housing above said receptacle, an outlet therein, a gutter combined with said housing over said reservoir having an outlet therein, a valve in said outlet controlled by the relative movement of one of said counterweights, a sealed tube, a pin extending laterally through said tube adjacent the center 10 thereof for pivotally supporting the same in horizontal position above said reservoir, a bracket on one end of said tube, a link attached to said bracket, a stopper on said link seated in said reservoir outlet, a ball weight free in said tube 15 to run between the said pin and the sealed end of the tube opposite to that carrying said bracket to outbalance said link and stopper for opening said reservoir outlet, a dish fixed on said tube at the end opposite to that carrying said bracket 20 and aligned under said gutter outlet, and drip apertures in said dish.

4. A window guard in combination comprising a housing including a gutter forming the top thereof, a reservoir for water, an outlet in said 25 reservoir, a faucet leading therefrom, a roller awning mounted in said housing, a receptacle on said awning, counterweight means adapted to outbalance said awning and receptacle, rain-actuated means for filling said receptacle from 30 said reservoir, and means actuated by said counterweight means to reset said filling means and shut off the supply of water from said reservoir.

5. A window guard in combination comprising a housing including a gutter forming the top 35 thereof, a reservoir for water, an outlet in said reservoir, a faucet leading therefrom, a roller awning mounted in said housing, a receptacle on said awning, counterweights adapted to outbalance said awning and receptacle, rain-actuated means for controlling the filling of said receptacle from said reservoir through said faucet, and a link slidably mounted on said reservoir under said filling means and extending into the path of one of said counterweights and adapted 40 to be raised thereby to restore said filling means to its normal position thereby to shut off the 45 water from the reservoir.

6. A window guard in combination comprising a housing including a gutter forming the top 50 thereof, a reservoir for water, an outlet in said reservoir, a roller awning mounted in said housing, a receptacle on said awning, counterweights adapted to outbalance said awning and receptacle, rain-actuated means for filling said receptacle from said reservoir, means actuated by one 55 of said counterweights to reset said filling means and shut off the water from said reservoir, vertical channel members adapted to be fixed to the sides of a window-casing, communicating 60 through the bottom of said housing with the interior thereof, and constituting shafts to receive and conceal said counterweights during movement thereof.

7. An automatic window guard comprising a 65 roller awning mounted in a housing, cord-attached counterweights connected to the roller, an open-mouthed receptacle on said awning having a plurality of drip outlets therein, a reservoir for water having an outlet and an overflow, 70 a gutter combined with said housing over said reservoir, an outlet in said gutter, a valve for said outlet, a bead on one of the counterweight cords, a loop member on said cord below said bead, a semi-flexible link connecting said loop 75

- with said valve, said bead being adapted to contact with said loop and open said valve when the counterweight on said cord is at its lowest position and said awning is rolled up, rain-actuated means for filling said receptacle from said reservoir to a predetermined level to outbalance said counterweights and cause lowering of the awning, means actuated by one of said counterweights to reset said filling means in its normal position and to shut off the supply of water from said reservoir, means for replenishing said reservoir with water and causing an overflow to replenish said receptacle continuously during a rain.
- 15 8. An automatic window-guard of the character described comprising a housing, a rotatably mounted awning normally concealed therein, a receptacle on said awning for facilitating the lowering thereof, drip outlets in said receptacle, 20 means combined with said housing for collecting rainwater, a reservoir for water combined with said housing, means directly actuated by rain at the commencement of a shower for controlling the dispensing of the rainwater from said reservoir into said receptacle to weight the same and cause the lowering of said awning, means for rewinding said awning automatically operable

when the rainwater in said receptacle has sunken to a predetermined level following cessation of a shower, and a plurality of valves in said collecting means normally closed to prevent evaporation of water in said reservoir but opening with a rise of rain water in said collecting means thereby to replenish the water in said reservoir. 5

9. An automatic window-guard of the character described comprising a roller awning mounted in a housing, a receptacle on the awning for facilitating the lowering thereof, a controlled drip outlet in the receptacle, a reservoir for water combined with the housing and having an overflow, rain-actuated means for controlling the dispensing of water from the reservoir to fill 15 the receptacle and cause lowering of the awning, a gutter combined with the housing for collecting rain-water, valves in said gutter adapted to open with a rise of rain-water therein for replenishing the reservoir and causing an overflow to 20 keep the receptacle filled, and means, automatically operable when the water draining from the receptacle reaches a predetermined level, for rewinding the awning and resetting the rain-actuated means. 25

OTTO VOGEL.
